OPENER GUARDS

Carl C. Wilm, Denver, Colo., assignor to Magnex, Inc.,
Denver, Colo., a corporation of Colorado

Application February 26, 1957, Serial No. 642,512

6 Claims. (Cl. 30—16)

This invention relates to a guard or shield for a container opener; more particularly, the invention relates to a shield suitable for use in conjunction with conventional punch-type can openers.

In modern practice, many beverages and other liquids are packaged in metal containers or cans which, when it is desired to dispense the contents, are opened with a punch-type opener. The conventional punch-type opener includes a handle, a fulcrum lug which engages the rim of the can, and a triangular punch element which forces a triangular segment of the can lid downwardly into the can to afford a pouring opening. With many beverages and other liquids, however, pressure within the can may cause the contents thereof to spew forth to a greater or lesser extent if the can is opened. This is particularly true of carbonated and malt beverages, including beer and ale, especially when the carbon-dioxide-containing liquid is relatively warm or has been agitated to some extent prior to opening. This can be most distressing to the person opening the can, particularly in those instances when the pressure is great enough to cause the discharged liquid to spray over a substantial distance.

In the past, a number of proposals have been advanced relating to shields or guards for preventing the spray from liquid containers opened with a punch-type opener from endangering the clothing of the person manipulating the openers. In general, these previously known shield or guard devices have been relatively complex and expensive and/or have required some modification of the opener itself in order to function properly. Inasmuch as openers of this type are relatively standardized devices and are extremely inexpensive, the aforesaid previously known guards have not been widely used.

A principal object of the invention, therefore, is a new and improved guard or shield device for a punch-type container opener.

A more specific object of the invention is the provision of a new and improved guard or shield for a punch type can opener which may be mounted upon the can opener without requiring any modification of the opener itself and which does not require any positive action on the part of the user to maintain the guard in place.

A further object of the invention is the provision of a new and improved punch-type opener guard which is extremely simple and inexpensive in construction.

A corollary object of the invention is a guard for a container opener of the type including both a punch-type opening device and a hook-type opener which permits effective operation of both portions of the opener without removal of the guard.

Thus, the invention relates to a guard for a container opener of the type comprising a handle of given dimensions, a punch extending from one end of the handle, and a fulcrum lug extending from the handle at a point adjacent the base of the punch. A guard constructed in accordance with the invention comprises a relatively thin, flexible, non-absorbent base member having a length substantially greater than the overall length of the opener;

2

this base member includes a handle section generally corresponding in dimensions to the handle of the opener and a shield section which extends from one end of the base member handle section and which preferably is substantially wider than the handle section. A first retainer strap is affixed to and extends across the major portion of the handle section of the base member. A relatively narrow second retainer strap extends across the handle section of the base member at the end thereof adjacent the shield section. Preferably, the two retainer straps are afforded simply by affixing to the base member a second similar thin, flexible, non-absorbent member and slitting the latter transversely of its handle section to define the desired straps. The two retainer straps and the handle section of the base member engage the handle, lug, and punch elements of the opener to mount the guard in predetermined position on the opener.

Other and further objects of the present invention will be apparent from the following description and claims 20 and are illustrated in the accompanying drawings which, by way of illustration, shows preferred embodiments of the present invention and the principles thereof and what I now consider to be the best mode in which I have contemplated applying these principles. Other embodiments 25 of the invention embodying the same or equivalent principles may be used and structural changes may be made as desired by those skilled in the art without departing from the present invention and the purview of the appended claims.

30 In the drawings:
Fig. 1 is a plan view of a can opener guard constructed in accordance with one embodiment of the invention;
Fig. 2 is a plan view of a slightly modified embodiment of the invention showing a conventional can opener 35 mounted therein;
Fig. 3 is a sectional view of the can opener guard of Fig. 2 taken along line 3—3 therein;

Fig. 4 is an elevation view showing the can opener and shield of Fig. 2 in operative position; and
40 Fig. 5 illustrates a structural detail relating to use of the hook type portion of the can opener.

The can opener guard 10 illustrated in Fig. 1 comprises a base member 11 having a handle section 12 and a shield section 13 which extends from the upper end of the handle section as seen in the drawings. Base member 11 is formed from a relatively thin, flexible, non-absorbent material, preferably one which is relatively light in weight. More specifically, the base member may be conveniently and inexpensively fabricated from vinyl plastic material 50 or other suitable plastics which are not detrimentally affected by beverages or other liquids with which a punch-type can opener is normally used. A liquid-proof fabric may also be employed for this purpose, but is not particularly desirable in most instances since it usually adds to 55 the cost of the guard without providing any marked improvement in operation.

The guard 10 further includes a first retainer strap 14 which is affixed to the handle section 12 of base member 11 and which extends across the major portion 60 of handle section 12. A second and relatively narrow retainer strap 15 is affixed to and extends across base member handle section 12 at the end thereof immediately adjacent the shield section 13. The retaining straps 14 and 15 may be conveniently and economically formed 65 by affixing to base member 11 a second guard member 16 which is essentially similar in configuration and structural characteristics to the base member 11. The two members 11 and 16 are affixed to each other about their peripheries by heat-sealing, in the case of plastics, or by sewing or other suitable means if water proofed fabrics are utilized in constructing the two members. 70 The member 16 is slit as indicated in the drawings at

17, 18 and 19 to afford the desired retainer straps 14 and 15.

5 Figs. 2 and 3 show a container opener 20 mounted in operative position in a guard 10A which is essentially similar to the guard 10 of Fig. 1 with the exception that guard 10A is provided with a permanent magnet 21 mounted on the shield section 13 of the guard at the end thereof opposite handle section 12. The can opener 20 is of conventional form and includes a handle 21, a triangular punch 22 extending from one end of the handle, and a fulcrum lug 23 extending from the handle at a point adjacent to but spaced from the base of the punch 22. Opener 20 may also include a conventional hook-type crown opener 24, it being common practice to combine this type of opener with the punch opener in devices intended for use in connection with carbonated beverages.

15 As shown in Figs. 2 and 3, the opener 20 is mounted in the guard 10 or 10A by sliding the handle portion 21 of the opener underneath the first retaining strap 14 of the guard and by engaging the second retainer strap 15 between the punch 22 and the fulcrum lug 23. With the guard thus mounted on the opener, the opener cannot slip free of the guard during normal usage. Consequently, no effort upon the part of the user is required to maintain the shield in operative relation to the opener. Preferably, the handle portion 12 of the shield is fabricated with dimensions generally corresponding to the dimensions of the handle portion of the opener in order to limit lateral movement of the opener with respect to the shield as much as possible and prevent it from sliding out of engagement with the shield straps. Moreover, the first retaining strap 14 is preferably made somewhat shorter than the handle portion 21 of the opener 20. This makes it possible to fold back the end 26 of the shield, as illustrated in Fig. 5, exposing the hook-type opener 24 for effective use without requiring removal of the shield from the opener. It will of course be apparent that if the opener 20 does not include a hook opener element it is not necessary that the retaining member or strap 14 be limited in length in this manner.

20 Fig. 4 shows the opener 20 and shield 10A in operative relation to a container 30. To open the lid 31 of the can 30, it is only necessary to pivot the opener 20 in a clockwise direction about the fulcrum afforded by the rim-engaging lug 23 in the usual manner to drive the punch element 22 of the opener through the can lid. If the contents of the can are under pressure and are forced from the can during the opening process, the liquid is prevented from escaping in an upward direction by shield portion 13 of the guard 10A which preferably covers substantially all of the can lid 31. The permanent magnet 21 serves to retain the shield portion 13 of the guard in position above the can lid 31. The permanent magnet is not essential in this regard, however, since the weight of the shield portion 13 is more than sufficient to hold the shield portion in proper position in the opening of beverages and like liquids. Thus, in normal operation of the opener the two guards 10 and 10A are essentially similar to each other. The permanent magnet 21 is highly advantageous, however, in that it affords a very convenient means for hanging the opener up when it is not in use. Moreover, if the shield section 13 of the guard 10A is folded over the punch 22 as indicated by dash outline 13A in Fig. 3, the magnet secures the shield in folded position, being attracted to the opener 20. In this position, shield section 13 forms a protective guard for the point of the punch and permits carrying the opener in the user's pocket, purse, or the like without danger thereto from the punch.

25 The can opener guard of the invention is extremely inexpensive and simple in construction, particularly when fabricated from two sheets of vinyl or similar plastics

as described hereinabove in connection with Fig. 1. The can opener may be permanently mounted within the guard without requiring any modification of the opener itself; for example, it is not necessary to affix rivets or other fastening devices to the opener or to provide apertures in the opener for receiving such fasteners. The guard is highly effective in containing and deflecting downwardly any liquid which may be discharged from a container during the opening process and thereby avoids the substantial inconvenience frequently encountered from use of this type of an opener, particularly with carbonated beverages.

30 Hence, while I have illustrated and described the preferred embodiments of my invention, it is to be understood that these are capable of variation and modification, and I therefore do not wish to be limited to the precise details set forth, but desire to avail myself of such changes and alterations as fall within the purview of the following claims.

I claim:

35 1. A guard for a container opener of the type comprising a handle of given dimensions, a punch extending from one end of the handle, and a fulcrum lug extending from the handle adjacent the base of the punch, said guard comprising a relatively thin, flexible, non-absorbent base member substantially greater in length than the overall length of the opener, said base member including a handle section having dimensions generally corresponding to the dimensions of the opener handle and a shield section extending from one end of the handle section, a first retainer strap affixed to and extending across the major portion of the handle section of the base member, and a relatively narrow second retainer strap extending across the handle section of the base member at the end thereof adjacent the shield section, the two retainer straps and the handle section of the guard being adapted to engage the handle, lug, and punch elements of the opener to mount the guard in predetermined position on the opener.

40 2. A guard for a container opener of the type comprising a handle of given dimensions, a punch extending from one end of the handle, a fulcrum lug extending from the handle adjacent the base of the punch, and a hook-type crown opener extending from the end of the opener handle opposite the punch, said guard comprising a relatively thin, flexible, non-absorbent base member substantially greater in length than the overall length of the opener, said base member including a handle section having dimensions generally corresponding to the dimensions of the opener handle and a shield section extending from one end of the handle section, a first retainer strap affixed to and extending across the major portion of the handle section of the base member and having a width no greater than the length of the opener handle, and a relatively narrow second retainer strap extending across the handle section of the base member at the end thereof adjacent the shield section, the two retainer straps and the handle section of the guard being adapted to engage the handle, lug, and punch elements of the opener to mount the guard in predetermined position on the opener.

45 3. A guard for a container opener of the type comprising a handle of given dimensions, a punch extending from one end of the handle, and a fulcrum lug extending from the handle adjacent the base of the punch in spaced relation thereto, said guard comprising a relatively thin, flexible, non-absorbent base member substantially greater in length than the overall length of the opener, said base member including a handle section having dimensions generally corresponding to the dimensions of the opener handle, and a shield section, substantially wider than the handle section, extending from one end of the handle section, a first retainer strap affixed to and extending across the major portion of the handle section of the base member, and a relatively narrow second retainer strap extending across the handle section of the base member at the end

thereof adjacent the shield section, first retainer strap and the handle section of the guard being adapted to engage the handle and lug elements of the opener and the second retainer strap and the handle section of the guard being adapted to engage the punch and lug elements of the 5 opener to mount the guard in predetermined position on the opener.

4. A guard for a container opener of the type comprising a handle of given dimensions, a punch extending from one end of the handle, and a fulcrum lug extending from the handle adjacent the base of the punch, said guard comprising a pair of relatively thin, flexible, non-absorbent guard members of similar configuration each substantially greater in length than the overall length of the 10 opener affixed to each other about their peripheries, said members each including a handle section having dimensions generally corresponding to the dimensions of the opener handle and a shield section extending from one end of the handle section, one of said members being slit transversely 15 of its handle section to afford a first retainer strap affixed to and extending across the major portion of the handle section of the guard and a relatively narrow second retainer strap extending across the handle section of the guard at the end thereof adjacent the shield section, the two retainer straps and the handle section of the other guard member being adapted to engage the handle, lug, and punch elements of the 20 opener to mount the guard in predetermined position on the opener.

5. A guard for a container opener of the type comprising a handle of given dimensions, a punch extending from one end of the handle, and a fulcrum lug extending from the handle adjacent the base of the punch, said guard comprising a pair of guard members of relatively thin, flexible, plastic substantially greater in length than the 25 overall length of the opener and peripherally sealed to each other, said members each including a handle section

30
35

having dimensions generally corresponding to the dimensions of the opener handle and a shield section extending from one end of the handle section, one of said members being slit transversely of its handle section to afford a first retainer strap affixed to and extending across the major portion of the handle section of the guard and having a width no greater than the length of the opener handle, and a relatively narrow second retainer strap extending across the handle section of the guard at the end thereof adjacent the shield section, the two retainer straps and the handle section of the other guard member being adapted to engage the handle, lug, and punch elements of the 10 opener to mount the guard in predetermined position on the opener.

6. A guard for a container opener of the type comprising a handle of given dimensions, a punch extending from one end of the handle, and a fulcrum lug extending from the handle adjacent the base of the punch, said guard comprising a relatively thin, flexible, non-absorbent base member substantially greater in length than the overall length 20 of the opener, said base member including a handle section having dimensions generally corresponding to the dimensions of the opener handle and a shield section extending from one end of the handle section, a first retainer strap affixed to and extending across the major portion of the handle section of the base member, a relatively narrow second retainer strap extending across the handle section of the base member at the end thereof adjacent the shield section, the two retainer straps and the handle 25 section of the guard being adapted to engage the handle, lug, and punch elements of the opener to mount the guard in predetermined position on the opener, and a permanent magnet mounted on the shield section of the base member at the end thereof opposite the handle section.
